UNITED STATES PATENT OFFICE.

WILLIAM McBRIDE, OF JERSEY CITY, NEW JERSEY.

CAR-COUPING.

SPECIFICATION forming part of Letters Patent No. 645,230, dated March 13, 1900.

Application filed December 18, 1899. Serial No. 740,624. (No model.)

To all whom it may concern:

Be it known that I, WILLIAM McBRIDE, a subject of the Queen of Great Britain, residing in Jersey City, in the county of Hudson 5 and State of New Jersey, have invented a certain new and useful Improvement in Car-Couplers, of which the following is a specification.

The invention relates to that class of couplers in which oppositely-placed hooks are arranged to automatically interlock; and the object of the invention is to provide a construction which shall engage with certainty, hold reliably against accidental disengagement, 15 and be easily uncoupled when required without risk to the operator.

It consists of a pair of hooked arms pivotally mounted one above the other on the draw-head of each car and forced toward the center line by the action of springs. The hook portions face toward each other and are adapted to engage each with a corresponding member on the next car. Provisions are made for separating the pairs by a single movement 25 either from the side or top of the car and for allowing a considerable range of motion in turning curves of short radius without liability of disengagement.

The invention also consists in certain details of construction and arrangement of parts 30 to be hereinafter described.

The accompanying drawings form a part of this specification and show what I consider the best form of carrying out the invention.

Figure 1 is an end elevation of a car-body 35 equipped with my improved coupler, and Fig. 2 is a plan view showing the coupler engaged and a portion of the framework of two adjacent cars.

Similar letters of reference indicate the 40 same parts in both the figures.

The mechanism on each car is a counterpart of that on the other, and a single description will suffice.

A is the buffer bar or beam, equipped with 45 spring-buffers A' and having an opening through which plays the draw-bar B, cushioned by the heavy rubber washers B', held in place by the nut B². The projecting portion B³ of the draw-head is widened and hollow, forming an upper and lower plate B⁴ B⁴,

through which passes the pin B⁵, carrying the swinging arms C, having the engaging hooks C'. The arms lie one upon the other, with the hooks facing toward the center line and urged 55 in this direction by the flat springs C² C², attached to the side plates of the draw-head.

In the act of coupling the rounded or beveled outer faces of the hooks are struck by similar faces on a corresponding pair on the 60 approaching car, and some or all the arms C on both cars are forced outward against the force of the springs C² until the hooks C' pass each other and spring into engagement, as shown, the upper hook on one car locking with 65 the oppositely-situated upper hook on the other car and the lower hook matching to its mate in like manner. It will be seen that by the double locking thus produced any angular movements of the cars tending to uncouple one pair tends to insure the engagement of the other, and the liability of unintentional or accidental release is reduced to a minimum.

The disengagement is effected by moving 75 the transverse bar D either by grasping the handle D' with a direct pull from the end of the buffer-bar or by the lever D², pivoted to the car front at D³ and extending sufficiently above the roof to be easily operated from that 70 point.

The bar D extends through a housing E on the buffer-bar and extends parallel therewith across to the other side of the car and is there pivoted at d to the crank-arm F' on the upper end of a short vertical shaft F, supported in a bearing F³, secured to the buffer-bar.

D⁴ is a socket attached to the bar D and receiving the lower end of the lever D².

At the lower end of the shaft F is an arm 90 F², extending outwardly opposite to the arm F', and is pivotally connected at f to a link G, having the longitudinal slot g' therein receiving the pivot h, by which a similar link H, pivoted at the opposite end to the lower arm 95 C, is attached.

J is a link similar to G, pivoted to the bar D at j near the housing E and having a slot j', in which rests the pivot k of the link K, corresponding to the link H described and attached to the uppermost arm C.

The endwise outward movement of the bar

D is communicated directly through the links J K to the upper hook and by the crank-arms F' F² and through the links G and H to the lower hook, spreading the arms against the resistance offered by the springs C² and freeing the hooks on the adjacent car, as will be understood.

The housing E serves as a guide for the bar D and also a more important function. It 10 closes a stiff helical spring L, abutting at one end against the interior of the housing and at the other against the fixed collar D⁵ on the bar and small enough to enter the housing when the spring is sufficiently compressed. The 15 spring offers no resistance to the movement of the bar in the direction to uncouple, but tends to hold the bar against movement inwardly, while allowing a limited extent of such movement when the line of draft is 20 strongly shifted laterally, as in turning curves or from other causes, and allows the line of draft to be thus shifted without offering an unyielding resistance to the motion, which through the links would tend to uncouple. 25 This spring L should be something stiffer than the springs C² C² on the draw-head, so that under usual conditions the inward movement of the bar D will be resisted and the hooks thus held normally sufficiently spread to be 30 in position to engage.

The slots g' j' in the links G and J afford sufficient lost motion to allow the arms C C to swing to the required extent in coupling without affecting the bar D and forcing it to 35 partake of the movement.

Modifications may be made in the forms and proportions of the several parts in adapting the invention to the conditions of railway and car construction under which it may 40 be called upon to serve.

Those portions of the mechanism not specifically described may be understood to be of any ordinary or approved construction.

I claim—

45 1. A draw bar and head, a pair of horizontally - swinging hooks carried thereby one above the other and facing toward the center line of said draw-bar, springs tending to move each of said hooks in such direction, a bar extending transversely of said hooks, fixed guides for said bar and connections to the latter from said hooks, and a spring serving as an abutment for said bar, thereby yieldingly limiting the said inward movement of said 50 hooks, all combined and arranged to serve with a corresponding mechanism in coupling cars, substantially as herein specified.

2. The draw-bar B and draw-head B³, pin B⁵ in the latter and two horizontally-swinging hooks centered on said pin one above the other, springs C² C² urging each of said hooks toward the center line of said draw-bar, the transverse bar D, shaft F connected to said bar, the arm F² on said shaft, and the links 60 J, K and G, H extending from said bar and arm to said hooks, all combined and arranged to serve with a corresponding mechanism in

coupling cars, substantially as herein specified.

3. The draw-bar B and draw-head B³, pin 70 B⁵ in the latter and two horizontally-swinging hooks centered one above the other on said pin, springs C² C² urging each of said hooks toward the center line of said draw-bar, the transverse bar D connected to said 75 hooks, the housing E and spring L therein tending yieldingly to limit such inward movement of said hooks all combined and arranged to serve with a corresponding mechanism in coupling cars, substantially as herein specified.

4. The draw-bar B and draw-head B³, pin B⁵ in the latter and two horizontally-swinging hooks C C', C C' centered one above the other on said pin, springs C² C² urging said 85 hooks toward the center line of said draw-head, the transverse bar D arm F' connected to said bar and carried by the shaft F, arm F² on said shaft, links G and H from said arm F² to one of said hooks, and links J, K from 90 said bar to the other of said hooks, all combined and arranged to serve with a corresponding mechanism in coupling cars, substantially as herein specified.

5. The draw-bar B and draw-head B³, pin 95 B⁵ in the latter and two horizontally-swinging hooks C C', C C' centered one above the other on said pin, springs C² C² urging said hooks toward the center line of said draw-head, the transverse bar D, the shaft F and 100 arm F' thereon connected to said bar, the arm F² on said shaft, and links G and H from said arm F² to one of said hooks, and links J and K from said bar to the other of said hooks, the housing E, spring L therein, and 105 collar D⁵ on said bar, all combined and arranged to serve with a corresponding mechanism in coupling cars, substantially as herein specified.

6. The draw-bar B and draw-head B³, pin 110 B⁵ in the latter and two horizontally-swinging hooks C C', C C' centered one above the other on said pin, springs C² C² urging said hooks toward the center line of said draw-head, the transverse bar D, the shaft F and 115 arm F' thereon connected to said bar, the arm F² on said shaft, and links G and H from said arm F² to one of said hooks, and links J and K from said bar to the other of said hooks, the housing E, spring L therein, and collar D⁵ 120 on said bar, and means as the slots g' and j' in the said links G and J and the pivots h and k on said links H and K received in said slots to afford the play required in separating the hooks in the act of coupling, all combined and 125 arranged to serve substantially as and for the purposes herein specified.

In testimony that I claim the invention above set forth I affix my signature in presence of two witnesses.

WILLIAM MCBRIDE.
